CLAIM

The ornamental design for a bottle opener as shown and described.

DESCRIPTION

FIG. 1 is a top perspective view of a bottle opener;
FIG. 2 is a bottom perspective view of the bottle opener of FIG. 1;

FIG. 3 is a top view of the bottle opener of FIG. 1;
FIG. 4 is a bottom view of the bottle opener of FIG. 1;
FIG. 5 is a front view of the bottle opener of FIG. 1;
FIG. 6 is a rear view of the bottle opener of FIG. 1;
FIG. 7 is a left-side view of the bottle opener of FIG. 1; and,
FIG. 8 is a right-side view of the bottle opener for FIG. 1.
All broken lines illustrate portions of the bottle opener that form no part of the claimed design.
